UNITED STATES PATENT OFFICE

ARTHUR A. JOHNSON, OF BRIDGEPORT, CONNECTICUT

MANIFOLDING

Application filed September 3, 1931. Serial No. 560,968.

This invention relates to manifolding, and more particularly, to a provision of a pile of continuous superposed record and interleaved transfer strips for use in typewriting machines and the like.

In practice in electrically operated typewriters and the like where a number of copies are to be made, it has been proposed before to provide superposed record strips having between them carbon or transfer strips running with the record strips, the record strips containing a succession of forms, usually printed, and between adjacent forms in a strip there is provided a designated tear-off point along which the strips may be severed into sheet or form lengths.

In my copending application, Serial No. 332,063, filed January 12, 1929, I have disclosed means for facilitating the stripping of the carbon or transfer sheets from a severed set of superposed record and transfer sheets after the writing operations have been completed.

In one of the forms of the invention illustrated in said application, this is accomplished by having lines of perforations, which are located between forms at the tear-off line, offset longitudinally in the record and transfer strips respectively, so that the record strips of a set project beyond the carbon strips at one end and the carbon strips project beyond the record strips at the other end to form finger-grips. This requires that the lines of perforations in the record and transfer strips respectively be offset depthwise of the pile and in a direction longitudinally of the pile.

In an application of Carl W. Brenn, Serial No. 528,528, filed April 8, 1931, now Patent No. 1,821,905 granted September 1, 1931, provision is made for facilitating stripping of the carbons from the record sheets of a severed set of sheets by offsetting the transfer and record strips laterally in the pile. These offset and projecting portions constitute feeding bands and have, in the preferred form, rows of pinwheel engaging apertures by means of which the strips are advanced over the writing surface of the typewriter or like machine. The apertured feeding

bands on the record strips were at one side of the pile while those on the carbon strips were at the other side of the pile. Accordingly, each kind of strips engaged only one of the pinwheels.

An object of this invention is to provide a pile of manifolding strips in which the apertured feeding bands may be at both lateral edges of both the record and carbon strips, or the apertured feeding bands of both kinds of strips may be at only one and the same side of the pile. This is accomplished, in the preferred form of my invention, by making only the edge portions of the feeding bands project instead of major portions thereof, as in said Brenn application, Serial No. 528,528.

In carrying out my present invention, the record and transfer strips may be offset in the manufacture of the pile and may be connected together by staples or the like in this offset condition. Or, if desired, the strips may have their edges in registry depthwise of the pile while in pack form, in which case the pin-apertures in the feeding bands on the different kinds of strips would be out of registration. In this form of the invention, the strips are left free to be shifted laterally when introduced to the typewriter to offset the edges of the strips and at the same time align the pin-apertures. This offset relation is maintained because of the engagement of the pinwheel pins in the aligned apertures and the shifting of the transfer, and record strips respectively is effected by the pinwheels and as a result of the feeding operation and takes places in a free stretch of the pile leading from the pack to the platen. This arrangement and method is described and claimed in my application Serial No. 560,967, filed September 3, 1931, covering a companion part of this invention.

Other features and advantages will herein-after appear.

In the accompanying drawings—

Figure 1 is a perspective view of a manifolding pack made in accordance with this invention.

Fig. 2 is a plan view of a pile of strips taken from the pack shown in Fig. 1.

Fig. 3 is a perspective view showing how the two kinds of sheets are separately gripped to be stripped from each other, in the form of the invention shown in Fig. 1.

5 Fig. 4 is a perspective view like Fig. 1, of another embodiment of this invention.

Fig. 5 is a transverse section through a layer of the pack shown in Fig. 4.

10 Fig. 6 is a perspective view showing a set of sheets severed after having been fed through the typewriter and indicating how the transfer sheets are stripped from the record sheets.

15 Fig. 7 is a perspective view of the pack, shown in Fig. 4, a typewriter platen and a stretch of strips from the pack to the platen, showing how the carbon strips are offset laterally from the record sheets as they approach the platen and remain in offset relation after they leave the platen.

20 Fig. 8 is a plan view showing the pile illustrated in Fig. 6 modified by omitting the rows of pin-engaging apertures at one side of the pile.

25 As shown in the accompanying drawings, the pile of manifolding strips may comprise record strips 10 and interleaved carbon strips 11 which are continuous in form and which are placed one above the other in superposed 30 relation. For convenience in shipping and handling, this pile of strips is preferably zigzag folded to form a pack or block 12, as shown in Fig. 1, from which the leading end may be lifted to be inserted in a typewriter 35 or like machine.

The zigzag folding of the pile of strips 10 and 11 is facilitated by transverse weakening lines 13, preferably perforations, in some or all of the strips and these further serve as 40 lines of severance along which the pile of strips may be severed to form sets of interleaved record sheets 10a and carbon sheets 11a, shown in Figs. 3 and 6.

45 In cases where it was desired to use the pile of strips 10 and 11 in a telegraphic typewriter having pinwheel feeding devices for keeping the pile in strict coordination with the platens of the sending and receiving machines, it was heretofore customary to provide the record strips 10 with lateral margins 50 projecting beyond the adjacent edges of the carbon strips so as to constitute feeding bands having apertures for engaging pins 14 on the typewriter platen 15, see Fig. 6.

55 In the application of Carl W. Brenn, Serial No. 528,528, now Patent No. 1,821,905, granted September 1, 1931, the stripping of the transfer sheets from the record sheets from a severed set of sheets was facilitated by providing feeding bands on the transfer strips 60 at one side of the pile while the feeding bands for the record strips were provided at the other side of the pile with both sets of feeding bands projecting beyond the adjacent edges 65 of the other strips. With this arrangement,

the transfer strips could only be engaged by one pinwheel while the record strips were engaged with the other pinwheel.

At times it may be desirable to have the pinwheel apertures provided at both side 70 margins of both record and transfer strips or to have the pinwheel apertures at only one margin of each strip but at the same side of the pile. Such an arrangement is made possible by the present invention. 75

As shown in Figs. 1 to 3, the record strips 10 have at each side margin feeding bands 16 while the transfer strips have at each side margin feeding bands 17, each feeding band 16 and 17 having pin-engaging apertures 19. 80 The strips 10 and 11 may be so superposed that the pinwheel apertures 19 are in registry, as shown in Fig. 2, and the strips may be secured together in this relation by staples 18 located on the lines of severance 13. 85

The pile of strips is led around the typewriter platen so that the pins 14 thereon engage the apertures 19 on the strips. After they are written upon, the strips may be torn along the lines of perforations 13 to form a set of superposed record sheets 10a and transfer sheets 11a as shown in Fig. 3. At this time it is usually desired to strip the transfer sheets from the record sheets and distribute the record sheets to various designated points. 95

For facilitating the stripping of the sheets 10a and 11a from each other, instead of having the entire feeding band projecting beyond the adjacent edge of the other kind of strip as proposed in the illustrated embodiment of the invention of the Brenn Patent No. 1,821,905, above referred to, the present invention merely makes the feeding bands 16 and 17 of the record and transfer strips respectively wider at opposite sides of the pile. That is to say, as shown in Fig. 2, the feeding band 16 at the left-hand side of the pile has an extension 20 reaching beyond the adjacent edge 21 of the transfer strip while at the right-hand side of the pile the feeding bands 17 on the transfer strips have extensions 22 projecting beyond the adjacent edges 23 of the record strips. Hence, in the severed set of sheets 10a and 11a, the extensions 20 and 22 are free to be gripped separately by the operator's hands and to be stripped apart by a spreading movement of the operator's hands while so gripping the extensions. 100

If desired, the apertures 19 at either side of the pile in both the record and transfer strips may be omitted in which case the strips may be fed and controlled by the apertures at only one side of the pile. Such an arrangement is shown in Fig. 8, but even in this case unapertured edges of the strips are preferably offset laterally, the transfer strips having extensions 22a reaching beyond the adjacent edge 23a of the record strip. 115

As taught in my copending application Serial No. 560,967, filed September 3, 1931, 120

of which this application is a companion part, the lateral edges of the transfer strips and record strips may be in alignment in the pack as shown in Fig. 4. When so arranged, the 5 manufacture of the pack is facilitated because ordinary guiding means may be employed to control the strips in the feeding and folding operations.

When the pack is so formed, the apertures 10 19 in the transfer and record strips respectively are offset laterally depthwise of the pile.

In this form of the invention, the strips 10 and 11 are not secured together by a staple, but are left free so that in introducing the 15 strips in the typewriter, the free stretch of strips 24 between the pack and the typewriter platen 15 may have the transfer strips and record strips shifted laterally to bring the apertures 19 on the two kinds of strips into 20 registry and cause the extensions 20 and 22 to project beyond the adjacent edges 21 and 23 respectively, to form the finger-grips for stripping purposes. The leading ends of the strips are placed on the typewriter platen 25 with the pins 14 extending into the registering apertures 19 in this condition and, as the feeding of the pile of strips continues, successive portions of the strips are offset laterally as they approach the typewriter platen 30 and as a result of the feeding operation.

Variations and modifications may be made within the scope of this invention and portions of the improvements may be used without others.

35 Having thus described the invention, what is claimed as new and for which it is desired to obtain Letters Patent, is:—

1. A pile of superposed and interleaved record and transfer strips each having at 40 each side margin a feeding band provided with a row of pinwheel-engaging apertures, the feeding bands of the record strips at one side of the pile projecting beyond the adjacent edges of the transfer strips and the 45 feeding bands of the transfer strips at the other side of the pile projecting beyond the adjacent edges of the record strips, the projecting feeding bands forming finger-grips for stripping purposes.

50 2. A pile of superposed and interleaved record and transfer strips each having at one side margin of the pile a feeding band provided with a row of pinwheel-engaging apertures, the edges of the feeding bands of the 55 record strips being offset laterally of the pile with relation to the edges of the feeding bands of the transfer strips so that the feeding bands of one kind of strips project beyond the feeding bands of the other kind of strips 60 to form finger-grips for stripping purposes.

3. A pile of superposed and interleaved record and transfer strips each having at one side margin of the pile a feeding band provided with a row of pinwheel-engaging apertures, the edges of the feeding bands of the 65

record strips being offset laterally of the pile with relation to the edges of the feeding bands of the transfer strips so that the feeding bands of one kind of strips project beyond the feeding bands of the other kind of strips, 70 the record strips and transfer strips having substantially the same width and having opposite edges of each kind of strip offset with relation to the opposite edges of the other kind of strips for stripping purposes. 75

Signed at Bridgeport, in the county of Fairfield, and State of Connecticut, this 25th day of August, 1931.

ARTHUR A. JOHNSON.
